UNITED STATES PATENT OFFICE.

JOSEPH GALAMB, OF DETROIT, MICHIGAN, ASSIGNOR TO FORD MOTOR COMPANY, OF DETROIT, MICHIGAN, A CORPORATION OF DELAWARE.

ELECTRIC SWITCH.

1,353,580.

Specification of Letters Patent. Patented Sept. 21, 1920.

Application filed May 16, 1919. Serial No. 297,459.

To all whom it may concern:

Be it known that I, JOSEPH GALAMB, a citizen of the United States of America, residing at Detroit, in the county of Wayne 5 and State of Michigan, have invented certain new and useful Improvements in Electric Switches, of which the following is a specification, reference being had therein to the accompanying drawings.

10 This invention relates to a control switch for the light and signal system of an automobile, and to an arrangement thereof that enables the operator to throw on lights and dim them, and to sound the horn or alarm, 15 the device being designed to be clamped on the steering column of the automobile.

The invention consists in the matters hereinafter set forth, and more particularly pointed out in the appended claims.

20 In the drawings,

Figure 1 is a view of a switch embodying the invention applied to the steering column of an automobile;

25 Fig. 2 is a view in longitudinal section through the switch;

Fig. 3 is a view in detail of a contact block;

Fig. 4 is a view in detail of a contact block on the under side thereof, and

30 Fig. 5 is a view of the assembled structure taken at right angles to the section of Fig. 2.

In the drawings, a holding member 1 is formed of sheet material so that when bent 35 between its ends the shank portion 2 thereof conforms to and encircles the steering column 3 for which the switch is intended. The opposed arms 4 of the device are transversely convexed, so as to form a tubular 40 barrel when closed with their margins 5 in contact or overlapping relation.

A knurled head 6 of suitable insulating material has a peripheral groove 7 that is entered by inturned flanges 8 on the ends 45 of the arms 4 so the head 6 has free rotation and slight longitudinal movement in the holder. A squared, flattened, or polygonal stem 9, non-rotatably embedded in the head 6, extends through a central opening in a contact block 10 of suitable insulating material which is held in place relative to the head 6 by suitable securing means, as for example, a screw 11 passing through depending lugs 12, embedded in the block

10 and likewise through the arms 4 of the 55 holder which it thus binds in position. A spring 13 in compression between the head 6 and the block 10 and around the stem 9 as a keeper normally projects the head 6 outwardly and at the same time abuts and 60 yieldingly forces inwardly a spring finger 14 that loosely encircles the stem 9 and is secured at its outer end to a bushing 15 which is peripherally channeled and roughened for non-rotatable embedment in the 65 block 10. A screw in the bushing forms with the latter a binding post or terminal connection for a conducting wire to the magneto or the generator of the automobile.

70 A contact bar 16 of spring material is non-rotatably secured on the stem 9 between the finger 14 and the block 10 so that inner projections 17 and 18 on its inner end portions, are yieldingly pressed both by the 75 finger 14 and the spring 13 against the block and face. When the contact bar is turned in to the position shown in Fig. 3, for example, the projection 17 drops into contact with the sleeve and screw of an embedded 80 terminal 19 arranged for connection with means for dimming the lights. Or the boss 18 may be swung into connection with a similar terminal 20 whereby full bright lights are obtained.

85 Recesses 21 and 22 in the block are used to lock the bar 16 in neutral position, the lugs snapping into these recesses. In order that the device may also close the circuit of an electric horn or like electric sounding 90 device, a terminal 26 with the externally channeled and roughened bushing of the other terminals, has an inwardly extending spring finger 23 that overlies the end of the stem 9 so as to contact therewith 95 when the head 6 is pushed bodily toward the block 10 against the resistance of the spring 13. As a matter of convenience this terminal 26 may be placed diametrically opposite the terminal 20 with the bushing and screw sufficiently below the surface of the block 10 so that the boss 17 yieldingly interlocks into the recess without touching the horn terminal 26, at the same time that the boss 18 contacts with the terminal 20, thus 100 holding the parts in adjustment.

105 As a further detail of good construction the stem 9 has a peripheral groove near its

outer end whereby a slotted washer 24 may be slipped into interlocking relation with the stem 9, the washer being seated in a recess 25, formed by counterboring the block 5 10. This permits the bodily withdrawal of the head 6 and block 10 together when the screw 11 that holds the arms 4 together and the block 10 in position, is withdrawn.

As a result of this construction a very 10 neat and simple switch is had that is easily mounted in position, is quickly manipulated to produce the desired lighting effect and is likewise arranged to close the circuit through the electric horn or other similar 15 sounding device, regardless of the position in which the handle may be set.

Obviously changes in the detail of construction may be made without departing 20 from the spirit of my invention and I do not care to limit myself to any particular form 25 or arrangement of parts.

What I claim is:

1. A controlling switch for the light and signal system of an automobile comprising 25 a casing adapted to be clamped around a steering post, a contact block secured in the casing, a head rotatable and longitudinally reciprocable in the end portion of the casing, a stem carried by the head extending 30 through the insulating block, means detachably securing the insulating block and stem together, a spring normally holding the head projected from the insulating block, a contact coöperating with the stem when the 35 head is moved toward the block to close a horn signal circuit, contact terminals for the various light circuits for which the switch is designed, mounted in the block, and a connecting arm carried by the stem for engaging the contact terminals and adapted 40 to interlock yieldingly with the contact block in desired position under the influence of the head-projecting spring.

2. The combination of a steering column 45 of an automobile with a light and signal circuit controlling switch consisting of a sheet metal casing bendable between the ends to conform to and embrace the column, the resultant arms forming an open-ended substantially cylindrical shell when the casing 50 is secured on the column, said arms having inturned flanges, a contact block provided with light circuit and signal circuit terminals and secured in the shell, a rotatable longitudinally reciprocable head having an annular groove to receive the flanges of the 55 shell and provided with members for engaging the several contact points when the head is appropriately rotated, said head being normally spring projected from the block, and contact members on the head and block for closing a horn signal circuit when the head is moved toward the block.

3. The combination of a steering column 60 of an automobile with a light and signal cir-

cuit controlling switch consisting of a sheet metal casing bendable between the ends to conform to and embrace the column, the resultant arms forming a substantially cylindrical shell when the casing is secured on the column, a contact block provided with light circuit and signal circuit terminals, means extending through said arms for securing the arms together and holding the contact block fixedly within the shell, a head 70 longitudinally reciprocable and rotatable in the casing provided with contact members adapted to be brought into contact with the terminals of the block, and a spring yieldingly projecting the head and permitting 75 the contact of a circuit terminal on the head with a companion terminal on the block to close the signal circuit when the head is forced inwardly, regardless of the relative angular positions of the block and head. 80

4. The combination of a steering column of an automobile with a light and signal circuit controlling switch consisting of a sheet metal casing bendable between the ends to conform to and embrace the column, the resultant arms being transversely concave to form a substantially cylindrical shell when the casing is secured on the column, a contact block provided with light circuit and signal circuit terminals and secured in the shell, a semicircular internal flange on the end portion of each arm, a head having a peripheral groove entered by the flanges of the closed shell whereby the head has rotatable and limited longitudinal reciprocating 90 movement in the shell, a spring between the contact block and head for holding the head normally projected, a stem non-rotatably secured to the head extending through the block, means detachably securing the block 95 and stem together, and means on the stem for forming electrical contacts selectively with the light terminals when the head is rotated and with the signal terminal when the head is forced inwardly to close the several 100 circuits of the terminals.

5. The combination of a steering column of an automobile with a light and signal circuit controlling switch consisting of a sheet metal casing bendable between the ends to conform to and embrace the column, the resultant arms being transversely concave to form a substantially cylindrical shell when the casing is secured on the column, a contact block provided with light 115 circuit and signal circuit terminals mounted in the shell, a head having a peripheral groove engaged by inner segmental flanges formed on the end portions of the arms, whereby the head is longitudinally reciprocable and rotatable in the casing, a stem extending from the head through the block and carrying contact members for engagement selectively with the block terminals, means detachably securing the stem and the 120

block, and a spring normally projecting the head from the block, and the head contact members against the block.

6. A controlling switch for the light and 5 signal system of an automobile comprising a cylindrical casing adapted to be secured to a steering column of an automobile, an inner retaining flange in the casing, a contact block secured in the casing, a head hav- 10 ing a peripheral groove spaced from its ends and engaged by the flange whereby the head extends within and has free rotatable and limited longitudinal movement in the casing, a stem secured to the head to turn 15 in the block through which it extends, light circuit and signal contact terminals in the block, a contact member rotated by the stem to engage the light circuit terminals selectively, a spring in compression between the 20 head and block yeldingly holding the stem contact member against the block and the head projected, and means on the head to close the circuit through the signal contact whenever the head is forced toward the 25 block.

7. In a controlling switch construction for light and signal circuits of automobiles, a fixedly positioned terminal carrying member having a flat face, said member having 30 a plurality of terminals carried thereby and exposed in said face and also having a finger, and a movable instrumentality positioned opposite said face, said instrumentality including a rotatable and axially mov- 35 able member carrying a stem non-circular in cross section at and extending into the terminal member and movable relatively thereto, a contact member fitting said stem to rotate therewith while permitting stem 40 movement axially relative thereto, said con-

tact member being positioned between said face and the finger, and resilient means between said finger and movable member for normally maintaining said latter member in an outer position.

8. In a controlling switch construction for light and signal circuits of automobiles, and wherein a movable member is adapted to control the lighting circuits by rotatable movements and the signal circuit by an axial movement, a terminal carrying member comprising an insulating block having a face adapted to oppose the movable member, terminal bushings exposed on said face and adapted to be connected to the lighting circuits, a bushing mounted in the block in spaced relation to said face and formed to receive a terminal of the signal circuit, and a rotatable member having a contact movable into and out of position relative to 50 said bushings, said contact having a configuration adapted to engage in a bushing.

9. In a controlling switch construction for light and signal circuits of automobiles, a member having a flat face and carrying 65 terminals of the light and signal circuits and a terminal for the supply circuit, said latter terminal including a finger overlying said face, and a contact carrying member movable relatively to the terminal-carrying member and having a contact positioned between said finger and face, whereby relative movement of contact and terminals will 70 make and break the circuits individually.

In testimony whereof I affix my signature 75 in the presence of two witnesses.

JOSEPH GALAMB.
